UNITED STATES PATENT OFFICE.

HARRY R. HIRST AND DANIEL UNGARO, OF TRENTON, NEW JERSEY.

CHALK-HOLDER.

1,114,693.

Specification of Letters Patent.

Patented Oct. 20, 1914.

Application filed June 13, 1913. Serial No. 773,570.

To all whom it may concern:

Be it known that we, HARRY R. HIRST and DANIEL UNGARO, citizens of the United States, residing at Trenton, in the county 5 of Mercer and State of New Jersey, have invented new and useful Improvements in Chalk-Holders, of which the following is a specification.

The invention relates to cue chalkers, and 10 more particularly to the class of extensible chalk holders.

The primary object of the invention is the provision of a chalk holder wherein the cube of chalk for chalking the tips of cues will be 15 held in a clamp which is carried upon a coiled extensible spring held within a case so that when it is desired to use the cube the spring will be extended from the case, and on the releasing of the cube the spring 20 will automatically wind, thereby bringing the cube out of the way of the player of a game of pool or billiards.

Another object of the invention is the provision of a chalk holder which is extremely 25 simple in construction, can be mounted at any convenient point so that the cube of chalk can be easily handled by the user, and when not in use will be held conveniently and out of the way of the player of 30 a game of billiards or pool.

A further object of the invention is the provision of a chalk holder which is extremely simple in construction, reliable and efficient in its purpose, and inexpensive in 35 manufacture.

With these and other objects in view, the invention consists in the construction, combination and arrangement of parts as will be hereinafter fully described, illustrated in 40 the accompanying drawing, and pointed out in the claim hereunto appended.

In the drawing: Figure 1 is a perspective view of the device or chalk holder constructed in accordance with the invention. 45 Fig. 2 is a side elevation of the holder with one of the cheek plates removed. Fig. 3 is a vertical transverse sectional view through the chalk clamp. Fig. 4 is a vertical sectional view through the chalk holder.

Similar reference characters indicate corresponding parts throughout the several views in the drawing.

Referring to the drawing by numerals, the chalk holder comprises a casing includ- 55 ing separable sections 5 and 6. The annular

rim 8 of the section 5 is designed to telescope upon the annular rim 9 of the section 6, and within this casing is held a coiled flat retractile spring 10, one end of which is fixed to a sleeve 11 tapped on to a bolt member 12 which is passed centrally through the sections 5 and 6, and this bolt member 12 carries a nut 13 which fastens the sections 5 and 6 together. The outer end of the spring is formed with a loop 14 in which is swiveled an eye member 15 from which is adapted to be suspended the chalk clamp presently described. The rims 8 and 9 of the sections 5 and 6 are provided with alining notches 16 through which is adapted 60 to work the spring 10 on the extending and retracting thereof. The section 5 has integrally formed therewith a perforated wing 17 through which is passed a suitable connection for fastening or hanging the casing 65 in suspension from the ceiling of a room over or adjacent to a pool or billiard table, as shown. Secured in the eye member 15 is one end of a flexible cord 20, on the opposite end of which is carried a chalk cube 70 clamp comprising a base 21 from which extends opposed resilient jaws 22 having in-turned spurs 23 adapted to bite into the chalk cube 24 which is engaged between the jaws 22 for the clamping of the same in the 75 said clamps.

When it is desired to use the chalk cube 24 the same is pulled upon, which causes the extending of the spring 10 from the casing, and after the tip of the cue has been chalked 80 in the ordinary well-known manner the cube 24 is released, whereupon the spring is retracted within the casing so that the said cube will be suspended within convenient 85 reach of a player of a game of billiards or pool, and in this manner the said cube is prevented from being misplaced or lost during the game.

From the foregoing it is thought that the construction and manner of operation of the 90 device will be clearly understood, and therefore a more extended explanation has been omitted.

What is claimed is:

A chalk holder comprising a casing 105 formed in two sections, the said sections being of substantially cup-shape, one being adapted to telescope over the other, a bolt member passed centrally through the sections connecting the same together, a sleeve 110

within the casing and fixed to the bolt member, a coiled retractile spring surrounding the sleeve and having one end fixed thereto and its opposite end projected exteriorly of the casing through the periphery thereof, and a cube holder having a flexible cord connected to the outer end of the spring.

In testimony whereof we affix our signatures in presence of two witnesses.

HARRY R. HIRST.
DANIEL UNGARO.
